FOREIGN PATENT DOCUMENTS

WO DM/072262 9/2009

* cited by examiner

Primary Examiner — Raphael Barkai(74) *Attorney, Agent, or Firm* — Briggs and Morgan, P.A.(57) **CLAIM**

The ornamental design for a video monitor, as shown and described.

DESCRIPTION

FIG. 1 is a front, top, and right side perspective view showing the design;

FIG. 2 is a front elevational view of the design;

FIG. 3 is a right side elevational view of the design;

FIG. 4 is a top view of the design;

FIG. 5 is a left side elevational view of the design;

FIG. 6 is a bottom view of the design; and,

FIG. 7 is a rear elevational view of the design.

It should be understood that the labels used herein for describing orientation (e.g., front, rear, top, bottom, right and left) are merely for reference, and the design may be disposed in any manner and still be within the scope of the present invention.
